UNITED STATES PATENT OFFICE.

PAUL A. FRANK, OF AKRON, OHIO.

RAZOR SHARPENER.

Application filed November 10, 1926. Serial No. 147,455.

This invention relates to sharpeners for razors and is an improvement upon that of my United States Patent No. 1,522,716, its chief objects being to provide a sharpener 5 adapted to be mounted upon and removed from the razor with economy of time and with assurance against cutting the stropping rolls of the sharpener, dulling the blade or cutting the hand in the mounting operation.

10 Of the accompanying drawings:

Fig. 1 is a section of my improved sharpener in place up on a razor.

Fig. 2 is a section of the same on the broken section line of Fig. 1, looking in the 15 direction of the arrow 2.

Fig. 3 is a section on the same line, looking in the direction of the arrow 3.

Referring to the drawings, the sharpener comprises a pair of journal shells 10, 11 20 hinged together by a shaft 12, the shells being formed with razor-clamping lugs 13, 13 adapted to be brought together upon the blade-journal ears 14, 14 of a safety razor having a pivoted blade 15, the said ears being formed with notches 16, 16 to receive the lugs and thus to position the sharpener upon the razor. The lugs 13 are preferably formed with shoulders, as shown at 13^a, 13^a, Fig. 1, to position the sharpener lengthwise 25 of the blade.

The shells are urged apart about their hinge shaft 12 by a hinge spring 17 so that they stand open for the reception of the razor until they are intentionally closed 30 upon it.

Journalized in each shell is an abrading or stropping roll 18 having at its end a gear 19 secured against relative rotation, the two gears being adapted to mesh when the shells 40 are brought together upon the razor and to be driven, through gearing hereinafter described, by a ratchet crank 20 mounted upon the shaft 12 and adapted to turn the same in only one direction.

45 For driving the rolls from the hand crank 20 the roll in the shell 10 has secured to its end opposite its gear 19 a gear 21 meshed with a small gear 22 which is journalized upon a stud 23 projecting from the inner face of 50 the shell, the gear 22 being meshed with a large gear 24 which is secured upon the hinge shaft 12, so that the gears 21, 22 and 24 remain entrained when the shells are opened and closed.

55 For oscillating the blade 15 a cam 25 is secured upon the shaft 12, and pivoted in the

respective shells 10, 11 at 27, 28 are a pair of blade-oscillating levers 29, 30 having their upper arms formed to coact with the cam 25 and having their lower arms formed at 60 their lower ends with lateral extensions 29^a, 30^a projecting to the middle of the device and there formed with terminal lugs, such as the lug 30^b, Fig. 1, adapted to engage the razor blade 15 at one middle position only, 65 the engagement of the blade at its middle providing substantially even pressure of the blade against the stropping roll along its length.

The cam 25 is adapted to swing one of 70 the levers 29, 30 in one direction and hold it to press the blade for a time against one of the rolls and then to swing the other of the two levers in the opposite direction and hold it to hold the blade for a time against 75 the other roll, each lever being held in contact with the cam by a pull spring 25^a connecting their upper arms, so that the blade-engaging portions of the levers are swung widely apart when the sharpener is opened 80 with the crank 20 in such position that the cam 25 is at neutral position.

For assuring that the cam 25 will be in such neutral position when the sharpener is opened for the insertion of the razor, so 85 that the levers 29, 30 will freely receive the blade between them without danger of cutting the rolls, the shells 10, 11 are formed with apertures 10^a, 11^a respectively adapted to register with each other when the sharpener is closed, and the handle 20^a of the crank 20 is made slid able in the latter and is adapted to lock the two shells together against the force of the hinge spring 17. The turning of the handle to locking position 90 thus assures that the cam will be properly positioned when the sharpener is again opened for the reception of the razor.

The form of the blade-oscillating levers is such that they may be of substantial 100 construction and yet exert a sufficiently yielding pressure upon the blade, the radial portions of their lower arms acting as torsion springs against which the lateral extensions 29^a, 30^a have substantial leverage, 105 and the blade itself being somewhat yielding.

The provision of the two blade-oscillating levers, mounted in the respective shells, especially with the provision for assuring 110 the proper positioning of the cam, provides for easy and safe mounting of the razor in

the sharpener, as the two levers swing widely away from each other in the opening out of the shells in which they are mounted, so that, the device being opened out, the razor 5 may be mounted therein simply by laying the razor in place against one side of the device and then closing down the other shell upon it, as distinguished from inserting the blade edge first between two closely spaced fingers, 10 as in my patent above referred to. This feature permits the employment of the enclosing shells, as it avoids the necessity of careful visual positioning of the blade and it also avoids the necessity of turning the cam 15 to a determinate position to permit the mounting of the razor in the sharpener.

The provision of journal shells instead of open frames also makes for safety in the 20 operation of the device and affords protection of its parts.

I claim:

1. A razor sharpener comprising a pair of frame structures adapted to be closed together upon the frame of a safety razor, 25 an abrading roll journaled on each frame structure, means for driving said rolls, and means for oscillating between said rolls a blade pivoted on the razor frame, the said oscillating means comprising members 30 mounted on the respective frame structures and adapted respectively to force the blade in opposite directions.

2. A razor as defined in claim 1 including means for compelling the blade-oscillating members to spread apart determinately in 35 their blade-engaging portions in the spreading apart of the said frame structures.

3. A razor sharpener comprising a pair of frames hinged together and adapted to be closed upon the pivotal mounting of a 40 razor blade, an abrading roll journaled on each of said frames, means for driving said rolls, a blade-oscillating lever fulcrumed on each of said frames, and means for actuating said levers. 45

4. A razor sharpener as defined in claim 3 in which the lever-actuating means comprises a cam journaled coaxially with relation to the hinge of the frames.

5. A razor sharpener comprising a pair 50 of shells pivoted together, an abrading roll journaled in each shell, gearing for driving the said rolls, a blade oscillating lever pivoted on each shell, a cam having drive connection with said gearing for actuating said 55 levers, means for maintaining the said levers in coacting relation to said cam when the shells are opened out, and means for assuring stoppage of said cam in a determinate position. 60

In witness whereof I have hereunto set my hand this 20th day of October, 1926.

PAUL A. FRANK.
